US00D715937S

(12) **United States Design Patent**
Pikkula et al.

(10) **Patent No.:** **US D715,937 S**
(45) **Date of Patent:** **** Oct. 21, 2014**

(54) **ORAL CANCER SCREENING DEVICE**

(71) Applicant: **Forward Science, LLC**, Sugar Land, TX (US)

(72) Inventors: **Brian Pikkula**, Sugar Land, TX (US); **Robert Whitman**, Houston, TX (US)

(73) Assignee: **Forward Science, LLC**, Sugar Land, TX (US)

(**) Term: **14 Years**

(21) Appl. No.: **29/445,273**

(22) Filed: **Feb. 8, 2013**

(51) LOC (10) Cl. **24-02**

(52) U.S. Cl.

USPC **D24/152**

(57) **CLAIM**

The design for the oral cancer screening device, as shown and described.

DESCRIPTION

FIG. 1 is a perspective view of the oral cancer screening device showing our new design;

FIG. 2 is a front view of the oral cancer screening device;

FIG. 3 is a rear view of the oral cancer screening device;

FIG. 4 is a right view of the oral cancer screening device;

FIG. 5 is a left view of the oral cancer screening device;

FIG. 6 is a top view of the oral cancer screening device; and,

FIG. 7 is a bottom view of the oral cancer screening device.
